UNITED STATES PATENT OFFICE

2,327,521

REINFORCED PLASTIC BUTTON

David S. Hart, Bethlehem, and Adelbert D. Cronk, Woodbury, Conn., assignors to The Patent Button Company, Waterbury, Conn., a corporation of Connecticut

Application September 6, 1940, Serial No. 355,698

1 Claim.

(Cl. 40—20)

Our invention relates to new and useful improvements in tack buttons, and more particularly to a molded plastic button which may be quickly and readily oriented in a special button-attaching machine of the type shown and described in the application filed by Frederick H. Peterson on June 23, 1939, for Orienting button-attaching machine, and bearing Serial Number 280,859.

One of the objects of the present invention is to provide a plastic button similar in type to the metal buttons shown in the patents to Frederick H. Peterson and Rollin R. Clarke, Numbers 2,170,091 and 2,170,092, dated August 22, 1939, for Tack buttons. In both of these patents, a metal button is so designed and constructed that it may be quickly and readily oriented in a button-attaching machine and its insignia will be in a readable position after the attaching operation.

A further object of the invention is to provide a plastic button that may be quickly and readily oriented, the button being formed of plastic but having molded therein a reinforcing metal vise to receive and deform the prong of a tack fastener to thus tightly hold the button to its cloth after the attaching operation.

Still another object of the invention is to provide a strong, relatively light-weight plastic button capable of being automatically oriented when fed through a special button-attaching machine, there being molded in the button head a vise to readily deform the prong of a tack, which vise is preferably of the form shown in the Frederick H. Peterson patent, Number 2,207,022, dated July 9, 1940, for Metal vise for tack buttons.

Still another object of the invention is to provide a plastic button which may be quickly and readily molded in large quantities, wherein the end of the hub is provided with means in the form of a wall for orienting the button when fed through a special button-attaching machine. Also, the hub has flats on its side walls parallel with the means on the end of the hub to thus hold the button in its oriented position as it passes down the chute of the button-attaching machine to the attaching station.

As is well known to those skilled in the art, tack buttons which are used on overalls and work clothes generally have a trade-mark or insignia or fanciful design on their tops, so that when a button is attached to the bib of an overall or to a strap or fastened to a work coat, it is desirable to have the insignia in a readable posi-

tion rather than upside down or at an angle to the eye of the observer.

Still another object of the invention is to provide a plastic button in which is molded a vise or anchor to not only form a deforming means for the prong of the tack fastener but also to prevent the plastic button head from splitting during the attaching operation.

Therefore, with these and other objects in view, the invention consists in certain new and novel arrangements and combination of parts, as will be hereinafter more fully described and pointed out in the claim.

Referring now to the drawing showing a preferred embodiment,

Fig. 1 shows a button attached to a strap;

Fig. 2 is a back view of the button;

Fig. 3 is a transverse sectional view of the button;

Fig. 4 is a similar view showing the button in its attached position; and

Fig. 5 is a side view of the button as shown passing through the slot of a hopper of an attaching machine, a fragment of which is indicated.

The hub with its aligning wall and flats is similar to the aligning wall and flats shown in the patent to Frederick H. Peterson, Number 2,170,091, granted August 22, 1939, for Tack buttons, with the exception that the angle of the aligning wall is changed with respect to the insignia, and is similar to the angle shown in the button in the application of Frederick H. Peterson for Orienting button-attaching machine, filed June 23, 1939, and bearing Serial Number 280,859.

Also, the vise shown in the present application may be similar to the one shown in the patent granted to Frederick H. Peterson on July 9, 1940, Number 2,207,022, for Metal vise for tack buttons, although a different form might be used without departing from the spirit and scope of the invention.

Referring now for the moment to Fig. 3, there is shown a plastic button having the head 1 and the integral plastic hub 2, while molded in the face of the head may be any desired brand, trade-mark or insignia 3.

Molded within the head 1 and the hub 2 may be seen the vise 4, similar to the vise shown in Patent 2,207,022, heretofore referred-to. This metal vise is perforate at the bottom, having the central opening 5 which is located near the outer end of the plastic hub. It will be noticed that the end of the plastic hub is open or provided

with a bore 5', which is slightly greater in diameter than the opening 5 in the metal vise. Thus, the prong of the tack will never contact with the relatively thin circular plastic walls of the hub, as if it did, it might tend to split either the hub or the button head itself. The vise has a top 6, so that the end of the prong 7 of a tack fastener 8, when driven up into the vise, will be deformed, as clearly shown in Fig. 4 to thus prevent its withdrawal and to hold the button firmly in its attached position.

The cap or top 6 of the vise 5 being located about centrally of the depth of the head permits a relatively thick layer of plastic above the top of the vise to thus enable the plastic button to better withstand the force of the impact when the tack is deformed within the vise.

It will be understood that during the attaching operation, there is a plunger (not shown) having a cavity conforming to the arcuate surface of the button head which fits over the button head, so that when the button is forced downwardly and the tack is driven up through the cloth 9 into the vise of the button, the button head is held in a "backed-up" position.

Referring now to the structure which makes it possible to orient the button in a special button-orienting and attaching machine, it will be noticed that the hub 2 is "flattened" on its one side, as at 10, and on its opposite side, as at 11, while extending parallel with the flats is a cut-away portion or notch 12 to form what we term an aligning wall 13. It will be noticed that the width of the bottom of the notched portion 12 is about the same as the thickness of the circular wall of the hub, so that there is no thin upstanding fin or wall on the hub where the notch or step cuts across the circular walls of the hub (Fig. 2).

The insignia 3 which, in the present instance, consists of the words "Big Mac" bears a definite relation with respect to the flats on the hub and the aligning wall on the end of the hub, and in this case, the aligning wall and flats appear at an angle of twenty degrees (20°) from a vertical line drawn through the center of the button, as shown in Fig. 1. The purpose of this is that the chute (not shown) leading from a hopper of the button-attaching machine also extends at an angle of twenty degrees (20°) from a line drawn through the center of the hopper and the attaching station. Therefore, by providing this compensating twenty-degree angle for the aligning wall and flats on the hub, when the buttons are attached the insignia will be in a true horizontal readable position.

In Fig. 5, there is partly illustrated the manner in which the button is properly oriented in a button-attaching machine of the type shown in the application of Frederick H. Peterson heretofore-mentioned, bearing Serial Number 280,859.

Briefly, the hopper for orienting the buttons consists of a base plate 14, on which the button rests, and the hub of the button can only pass through the groove 15 when the one flat 11 is adjacent the wall 16 and the other flat 10 is ad-

5 jacent the wall 17 and, most important, the eccentric aligning wall 13 of the notch 12 registering with the wall 18, which latter is a defining part of the groove 15.

It will be remembered that the button is in an inverted position when in the hopper and then passes down the chute (not shown) where it is turned over rightside up, so that the reading matter of the insignia 3 will be in the position as shown in Fig. 1.

When the button is formed in this manner, that is, with the aligning wall and the flats on the hub, the button can only pass through the hopper, due to the aligning wall, in one oriented position, while the flats, in turn, will hold the button in its properly oriented position as it travels down to the attaching station. Thus, when the button is finally attached, the insignia will be in its true horizontal readable position.

The buttons, of course, will be made in molds having a plurality of die cavities but the manner of molding the buttons forms no part of the present invention.

By forming the button head in the manner above-illustrated and described, it will be seen that a relatively inexpensive, strong plastic button is obtained which will withstand the usage to which it is to be put and will also withstand the shock from the attaching operation without in any way damaging the button.

Furthermore, the button head with its insignia may be properly oriented, so that the reading matter is always in the desired alignment.

Finally, it will be understood that a different form of vise might be molded within the button, but we have found the one illustrated to be very satisfactory.

Many slight changes might be made without departing from the spirit and scope of the invention.

Having thus described our invention, what we claim as new and desire to secure by Letters Patent is:

An orientatable reinforced plastic button head of the tack fastener type including a centrally located hollow hub, the button head having a centrally located internal chamber of larger diameter than the diameter of the hub and the hollow hub registering with said chamber, reinforcing means within said chamber and partially filling the hollow hub, said reinforcing means in said chamber adapted to receive and deform a tack fastener, said hub having flats on the opposite external sides thereof and extending throughout the depth of the hub, a portion of the lower end of the peripheral wall of the hub being omitted just below the lower end of the reinforcing means and on one side of the hub to form an aligning wall parallel to said flats, and the aligning wall extending tangentially to the internal defining wall of the hub, and indicia on the face of the button head extending at an angle to the flats and the said aligning wall.
